2 Claims. (Cl. 214—140)

The present invention relates to a wheel-supported loader equipped with a shovel which is supported by arms pivotally connected to the loader frame and movable up and down by means of cylinder-piston devices. The pivot of the arms is situated behind the front wheel axle of the loader, and the shovel is pivotally mounted at the free ends of said arms and actuated by means of at least one cylinder-piston device between the shovel and said arms.

Previously known loaders of this kind have a very serious disadvantage, especially when used for loading ore in mines in that the tire wear becomes abnormally great. Therefore, it has not been economically feasible to use loaders of this kind, even if for other reasons it would have been desirable.

To remove this disadvantage it has been proposed to raise in a suitable way, normally by means of hydraulic jacks, that end of the loader which has to take up the load during use of the shovel so that the wheels on the same end are brought out of contact with the ground. It is to be noted that the most dangerous load as far as wear on the tires is concerned arises during loosening of the material in the filling of the shovel while the load to which the tires are subjected after the filling of the shovel and during the raising of the shovel is of less importance. Another force which occurs during the filling of the shovel is the backward force which the shovel exerts on the loader and which tends to move the loader backwards on the ground. This causes the tires to slide on the ground resulting in a substantial amount of wear. Also this disadvantage is removed by the previously proposed raising of the end of the loader carrying the shovel.

This known means for removing the above mentioned disadvantages is, however, not satisfactory, as it makes the loader much more complicated due to the necessity of special jacks for carrying out the raising movement and also due to the additional maneuvering of the loader that must be done by the driver during every loading action. This maneuvering requires the driver to first drive the loader forwards to the loading position, then has to effect the necessary raising of the end of the loader, and finally, after the filling of the shovel to lower the end to make it possible to drive the loader to the emptying place. This means that a whole loading and emptying cycle will take a considerably longer time than in a loading operation which does not require the raising of an end without relieving the wheels lying closest to the shovel of load.

The object of the present invention is to solve the problems arising during loading in a considerably easier and simpler manner than discussed above. The invention is substantially characterized in that the arms between their ends are provided with a support means which consists of support blocks cooperating with the upper side of each wheel and which, in the lowered position of the arms and thus in the unloaded condition of the cylinder-piston devices cooperating with said arms said blocks are pressed against the upper side of the wheels thus causing

2

a raising force of the loader so that the wheel axle relieved of the load.

The invention will be further explained in connection with the attached drawing showing an embodiment of the invention in side elevation.

The loader, which may be in the form of a track loader, the frame of which is denoted by the reference number 1, has a conventional appearance, and includes comparatively large wheels 2. On each side of the drive cabin (not shown) is provided a bracket 3 at which load beam comprising two arms 4, one of which is shown. The beam is pivotally mounted and at its free end carries a load shovel 5. The pivot shaft 6 of the load beam is situated above and behind the axle of the wheels 2. The raising and lowering movement of the load beam is obtained by means of a cylinder-piston device located between each bracket 3 and the associated arm. The load shovel 5 which can be constructed in a manner known per se, is pivotally mounted near its upper end around a shaft 8 provided between the free ends of the arms 4. The pivot movement of the shovel takes place by means of a pair of cylinder-piston devices 9 which are provided between the arms 4 and the back wall of the shovel. As seen in the drawing, the shovel is provided with a number of connecting holes for making possible to change the turning radius of the forward end of the shovel.

According to the present invention the two arms 4 of the load beam carry support means 17 which, in the lowered position of the beam, are adapted to rest on the upper side of the respective tractor wheel 2. When the cylinder-piston devices cooperating with the load beam are unloaded, the support means 17 press against the upper side of the wheels and thus cause the intended raising force on the tractor so that the wheel axles are loaded. This support means consists of a support block connected to each beam arm 4 and which at the side facing the tire has a shape substantially corresponding to the outer diameter of the tire so that the load is transmitted to the tire along the greatest possible surface.

The invention is not limited to the above described embodiment but can be changed in several ways within the scope of the following claims.

I claim:

1. In a loading vehicle including a frame and group of wheels supporting the frame; a loading assembly comprising arms pivotally connected to and extending laterally from the frame and having outer free ends, shovel carried by the arms, said shovel being pivotally maintained on the free ends of the arms, means connecting between the arms and shovel for actuating the shovel, a support block members fixed to the undersides of the arms and adapted to rest on top of the wheels in the lowered position of the arms so that, as the shovel is being filled, the arms are supported on the wheels.

2. The combination of claim 1, wherein said support block members have undersides cooperating with the wheels and having a shape substantially corresponding to the outer diameter of the wheels in order to obtain the maximum possible contact surface between the blocks and the wheels.
